(57) **CLAIM**

The ornamental design for a semiconductor light emitting module, as shown and described.

DESCRIPTION

FIG. 1 is a front view of a semiconductor light emitting diode module in accordance with the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof; and,

FIG. 9 shows a semiconductor light emitting module in an environment of use thereof.

The broken lines seen in the drawings are for the purpose of showing environmental structure, and form no part of the claimed design.
